13 Claims

The present invention relates in general to altitude control systems and in particular is an improved method and means for ascertaining the depth of a submarine vehicle and producing an error signal proportional to the deviation from a predetermined control altitude level. Furthermore, and even more specifically, it is a transistorized, compact sonar echo-ranging circuit that produces a negative, substantially square wave type of signal, having a time duration that is a function of the altitude of the transducer above the sea floor at any given instant.

In the past, altitude control systems and comparable echo-ranging systems have been employed successfully for many practical purposes. However, for the most part, such systems have been quite large and heavy which makes them somewhat burdensome to handle and the power requirements for the operation thereof were considerable and, likewise, were somewhat burdensome. Moreover, in many instances, the reliability of similar prior art devices left a great deal to be desired.

The instant invention overcomes to a considerable extent the disadvantages of the prior art devices because it is compact, light in weight, susceptible to being manufactured as a printed circuit board, and requires only a small power supply.

It is, therefore, an object of this invention to provide an improved altitude control system.

Another object of this invention is to provide an improved contour follower system.

Another object of this invention is to provide an improved method and means of sensing and controlling the depth at which a submarine vehicle runs with respect to the ocean bottom.

Another object of this invention is to provide an improved method and means for automatically maintaining a towed depth charge within a specified stratum above the bottom of the sea.

Still another object of this invention is to provide an improved echo-ranging system.

A further object of this invention is to provide a transistorized transmit-receive circuit for an echo-search system.

A further object of this invention is to provide an improved transistorized echo-ranging system that is small in size, light in weight, and reliable in operation.

Another object of this invention is to provide an improved transistorized echo-ranging system that has increased accuracy as a result of temperature compensation being incorporated therein.

Still another object of this invention is to provide a transistorized transmit-receive circuit that may be readily mounted as a printed circuit board.

Another object of this invention is to provide an echo-ranging system that has only relatively small power requirements.

Other objects and many of the attendant advantages will be readily appreciated as the subject invention be-

2

comes better understood by reference to the following detailed description when considered in conjunction with the accompanying drawing wherein:

FIG. 1 is a block diagram of the altitude control system incorporating this invention; and

FIGS. 2A and 2B combine to form a schematic circuit diagram of the echo-ranging portion of the subject invention.

Referring now to FIG. 1, there is shown an altitude control system comprising a tuned free-running, blocking oscillator 11 with the output thereof connected through a toroidal transformer 12 to the input of an electro-acoustical transducer 13. Transducer 13 is the reversible type that converts electrical energy into proportional acoustical energy and vice versa. The output thereof is applied to the aforesaid transformer 12 during receiving operations, as will be further explained subsequently.

Toroidal transformer 12, thus, has one of its outputs coupled to a transmit-receive (TR) circuit 14 which is adapted for passing all received echo signals but stops practically all originally transmitted search signals so that they will not be processed as received signals or otherwise cause signal distortion to exist. The output of TR circuit 14 is coupled through a tuned amplifier 15, a tuned transformer 16, another tuned amplifier 17, another tuned transformer 18, and another amplifier 19 to an emitter follower 21.

The output of emitter follower 21 is supplied to an amplifier 22, the output of which is coupled to a shunt detector 23 which, of course, is so designed as to shunt to ground that component of the echo signal having the same frequency as the output signal from blocking oscillator 11. The output from shunt detector 23 is then clipped by a clipper-limiter 24 and again detected by a diode 25 so as to produce a direct current envelope output signal therefrom. This DC envelope output signal is supplied to one of the inputs of a one-shot multivibrator 26 to timely turn it off after it was originally triggered and turned on by a transmit pulse supplied thereto from the aforesaid blocking oscillator 11, as a result of the original search signal transmission.

The output of multivibrator 26 is then fed through a circuit isolation emitter follower 27 before being limited by Zener diode limiter 28, after which it is coupled through a relay 29 to the input of a utilization apparatus controller 31. While, in this particular case, the input signal to controller 31 is supplied from relay 29, it could be obtained for many suitable purposes from the output of Zener limiter 28, since so doing would obviously be well within the purview of one skilled in the art having the benefit of the teachings herein presented.

The input to controller 31 is actually supplied to a squarewave detector and control amplifier 32, the output of which is connected to up-down relays 33 which, in turn, operate the motor of a winch 34. A cable 35 from winch 34 is connected to the towed submarine vehicle or other utilization apparatus whose altitude above the sea floor is being controlled. Of course, pulling in said cable raises the vehicle and paying out said cable causes it to be lowered.

In order to improve the accuracy of altitude control, a plurality of bias voltage regulation thermistors 36, 37, and 38 are respectively incorporated in the circuits of tuned amplifier 15, tuned transformer 16, and one-shot multivibrator 26. Thus, temperature compensation therefor is effected which, in turn, effects improved circuit

stability and overall accuracy, even during ambient temperature fluctuations.

Referring now to the detailed circuit diagram of FIGS. 2A and 2B, the echo-ranging portion of the subject invention is disclosed as including a B- voltage 40 and a ground 41. Between said B- voltage and ground, a power supply filter 42, containing a pair of voltage stabilization capacitors 43 and 44, is connected, and to the negative side of said stabilization capacitors is connected the collector of a 2N174A PNP transistor 45 of blocking oscillator 11. The base thereof is connected through a resistor 46 to the side of stabilization capacitors 43 and 44. Likewise, the base of transistor 45 is coupled through a capacitor 47 to one terminal of a primary winding 48 of the aforementioned toroidal transformer 12, with the other end terminal of said transformer coupled to ground. The emitter of transistor 45 is coupled to a center tap of said primary winding 48 of transformer 12. A secondary winding 49 thereof has one terminal connected to the aforesaid transducer 13 and the other terminal thereof is coupled to the aforementioned transmit-receive circuit 14, consisting of a pair of reversed polarity diodes 51 and 52 that are connected in parallel with each other and in series with a capacitor 53, the positive side of which is coupled to ground. Another voltage stabilization capacitor 54 is included in tuned amplifier circuit 15 along with a 2N331 PNP transistor 55. The base of transistor 55 is coupled through a resistor 56 to a slightly reduced B- voltage. Reduction in said B- voltage is, of course, effected by a resistor 57 inserted in the B- voltage line. Since for all practical purposes said reduced B- voltage still constitutes a B- voltage, it will be referred to in that manner in the remaining discussion of the subject circuit to follow.

The base of the aforesaid transistor 55 of tuned amplifier 15 is also connected through a thermistor 36 to ground, and a capacitor 58 is parallel coupled therewith. The emitter of transistor 55 is coupled through a resistor 59 to ground and is also connected to the negative voltage terminals of the aforesaid reversed polarity diodes 51 and 52, since these terminals effectively constitute the output of the aforesaid transmit-receive circuit 14. The collector of transistor 55 is connected to a predetermined intermediate turn of a primary winding 61 of tuned transformer 16. Coupled in parallel with said winding 61 is a capacitor 62, and between one terminal thereof and the aforesaid B- voltage is connected resistor 63.

The output of transformer 16 is taken across a secondary winding 64 thereof, one terminal of which is connected through parallel connected thermistor 37 and capacitor 65 to ground, and through a resistor 67 to the B- voltage, with the other terminal thereof connected to the base of a 2N331 PNP transistor 66 incorporated in the aforementioned tuned amplifier 17. The emitter of transistor 66 is connected through a parallel connected resistor 68 and capacitor 69 to ground, and the collector thereof is connected to a predetermined intermediate turn of a primary winding 70 of the aforementioned tuned transformer 18. The end terminals of primary winding 70 has coupled in parallel therewith a capacitor 71 and a diode 72, and one terminal thereof is connected through a resistor 73 to B-. A secondary winding 74 of transformer 18 has one of the terminals thereof connected through a resistor 75 to B- and through a resistor 76 and a capacitor 77 parallel connected therewith to ground.

The other terminal of secondary winding 74 of transformer 18 is coupled to the base of a 2N331 PNP transistor 78 which is incorporated in the aforementioned amplifier circuit 19. The emitter thereof is connected through parallel connected resistor 79 and capacitor 81 to ground, and the collector thereof is connected through a resistor 82 to B-.

A coupling capacitor 83 is connected between the collector output of transistor 78 and the base input of another 2N331 PNP transistor 84 of the aforementioned

emitter follower circuit 21. The base of transistor 84 is also coupled through a resistor 85 to B- and through another resistor 86 to ground. The collector of transistor 84 is direct coupled to the B- voltage, and the emitter thereof is coupled through a resistor 87 to ground. Inasmuch as transistor 84 is incorporated in an emitter follower circuit, the output is taken from the emitter thereof and coupled through a coupling capacitor 88 to the base of a 2N331 PNP transistor 89 located in the aforementioned amplifier circuit 22, biased by voltage divider network consisting of resistors 80 and 90. The emitter thereof is coupled through a resistor 91 and capacitor 92 connected in parallel therewith to ground, and the collector thereof is connected through a resistor 93 and a capacitor 94 connected in parallel therewith, said resistor 93 and capacitor 94 constituting the aforementioned shunt detector 23.

The output of amplifier 22 is taken from the collector of transistor 89 and is coupled through a coupling capacitor 95 to the input of clipper circuit 24 consisting of parallel connected resistor 96 and diode 97, one terminal of which is coupled to ground. The output of capacitor 95 is likewise coupled through the aforementioned diode 25 and a resistor 98 to ground, and the junction of said diode 25 and resistor 98 is connected through another capacitor 99 to the input of the aforementioned one-shot multivibrator 26.

Actually, the output of diode detector 25 is effectively supplied to the base input of a 2N331 PNP transistor 101. The base thereof is also connected through the aforementioned thermistor 38 and a resistor 102 connected in parallel therewith to ground. The emitter of transistor 101 is coupled through a resistor 103 to ground and to the emitter of another 2N331 PNP transistor 104. The collector of transistor 101 is connected through a resistor 105 to the aforesaid reduced B- voltage. Furthermore, said collector is coupled through a series connected resistor 106 and capacitor 107 to the emitter of PNP transistor 45 of blocking oscillator circuit 11 mentioned above. Connected between the junction of resistor 106 and capacitor 107 and ground is another capacitor 108.

The collector of transistor 101 is coupled through a pair of coupling capacitors 109 and 111 to the base of transistor 104 and through a resistor 112 to B-. The collector of transistor 104 is coupled through another resistor 113 to B- and through another resistor 114 to the output of the aforementioned capacitor 99 immediately following diode detector circuit 25. Of course, said transistors 101 and 104 and their associated circuitry constitutes one-shot multivibrator 26.

The output of multivibrator 26 is taken from the collector of transistor 104 and is fed through a resistor 115 to the base of a 2N331 PNP transistor 116 located in emitter follower circuit 27. The collector of transistor 116 is coupled directly to the reduced B- voltage, and the emitter thereof is coupled through a resistor 117 to ground. Since the emitter of transistor 116 constitutes the output of emitter follower 27 it is coupled through a coupling capacitor 118 to Zener diode 28 which likewise has its other terminal connected to ground. As may readily be seen, diode 28 constitutes the aforementioned Zener limiter which limits the output voltage to an optimum predetermined value.

The output of Zener limiter 28 is taken from the junction thereof and capacitor 118 and is supplied through a resistor 119 to stationary switch contact 121 of the aforementioned relay 29. Actually, if so desired, the output from either Zener limiter 28 or resistor 119 may be considered the output of the echo-ranging portion of the subject invention. However, in this particular case, said output is preferably supplied through relay 29 in order to facilitate the coupling thereof to the particular utilization apparatus controller depicted in FIG. 1 and for other functional purposes not included herewith. Hence, said relay may or may not be included within the subject

invention, since so doing in either case would obviously be well within the purview of one skilled in the art having the benefit of the teachings herein presented, in order to provide optimum use thereof under any given operable circumstances.

In order to be consistent with the device of FIG. 1 and to provide continuity between the echo-ranging portion of this invention and utilization apparatus controller 31 herein employed, relay 29 will be described in brief. As previously mentioned, the output of Zener limiter 28 is effectively applied to stationary switch contact 121 of relay 29. Relay 29, of course, has a pair of single throw-double pole switches 122 and 123 which are actuated by a solenoid 124. Coupled in parallel with solenoid 124 is a diode 125 and one terminal thereof is coupled to a reversely polarized diode 126 to ground in order to insure that the appropriate direct current is supplied to solenoid 124, inasmuch as it is preferably a direct current solenoid. The circuit of solenoid 124 is completed by connecting one terminal thereof to a fixed switch contact 127 of switch portion 123 and the movable arm contact 128 of switch portion 122. In this particular case, another stationary switch contact 129 of relay switch 122 is left blank, but, if so desired, may be utilized for supplying electrical current to any other desired utilization apparatus not shown herein. Another stationary contact 131 of relay 29 is coupled to the aforementioned B-, and a movable arm 132 thereof (ganged with movable arm 128) is connected to the negative pole of a 12 volt direct current battery 133. The positive pole thereof is coupled through a fuse 134 to the negative pole of another 12 volt direct current battery 135, the positive pole of which is coupled through a pressure switch 136 to ground. Thus, batteries 133 and 135 effectively supply the aforementioned B- voltage to the entire echo-ranging circuit. As may readily be seen, the output of relay 29 is effectively taken from the movable arm 128 of switch 122 and this occurs as a result of movable arm 128 and stationary contact 121 normally being in an initially closed position prior to the energization of solenoid 124 by the application of a voltage thereto from some other source (not shown) that is greater than the maximum negative square wave output voltage from Zener limiter 28. Thus, in this case, it may be seen that when relay 29 is energized, the utilization apparatus controller is disconnected from the output of the echo-ranging circuit.

Briefly, the operation of the subject invention is discussed in conjunction with FIGS. 1, 2A, and 2B as follows:

Freerunning blocking oscillator 11 is preferably designed to produce an output signal having a frequency of the order of sixty-five kilocycles per second. This signal is simultaneously applied through transformer 12 to transducer 13 and to one-shot multivibrator 26 to trigger it and thereby produce the front edge of a negative square wave output signal. The negative portion of said square wave output signal continues in duration and, consequently, in length until such time as multivibrator 26 is turned off by the received echo signal, unless such duration exceeds twelve milliseconds. Multivibrator 26 is, accordingly, designed to produce a negative going square wave having a time constant of twelve milliseconds because this amount of time corresponds to a transmit-receive distance of thirty feet in water, the maximum range desired in this particular embodiment.

During the transmission period, transducer 13 broadcasts acoustical energy into the sea water and, in this case, it is preferably directed toward the sea floor so as to effectively determine the distance thereto at any given instant. To substantially eliminate any of the transmitted signal from being passed on to the receiver portion of this invention, transmit-receive circuit 14, comprising a pair of parallel reversed polarity diodes (see FIG. 2A), bypasses to ground all components of the aforesaid sixty-five kilocycle per second signal having an amplitude or

strength exceeding a predetermined design value. For most practical purposes, this limiting or signal-stopping function prevents signal distortion sufficiently to provide an adequate signal-to-noise ratio; however, subsequent processing and shunt detector 23 improve the situation by causing the sixty-five kilocycle signal, if any, that got through transmit-receive circuit 14 to be filtered out and shunted to ground, thereby preventing an adverse effect on the operation of one-shot multivibrator 26 during the receive period thereof.

The echo-signal from the sea floor (or other target, as the case may be) occurs sometime between the zero time of transmission and expiration of twelve milliseconds if the altitude or depth being measured is less than thirty feet. As a result of its being originally broadcast within a multi-molecule subaqueous medium, reflected from a possible target, and perhaps modified due to the presence of Doppler, said echo signal is received as a multi-frequency intelligence signal, which ordinarily includes as a component thereof the originally broadcast seventy-five kilocycle per frequency signal. This echo is sensed by transducer 13, passed through transmit-receive circuit 14, amplified, filtered, and shaped in tuned amplifier 17, tuned transformer 18, and amplifier 19, respectively. Then it is passed through circuit isolation emitter follower 21 and further amplified by amplifier 22 before being applied to shunt detector 23. In shunt detector 23, any sixty-five kilocycle per second component that may still exist in the return signal is effectively bypassed to ground, and the remaining intelligence signal is passed on to be clipped by clipper-limiter 24. Because removal of the broadcast frequency is primarily important during the transmit situation in order to prevent it from triggering multivibrator 26 and turning it off rather than on at that time, shunt detector 23 was incorporated in the subject system; however, during the receive situation whether or not the broadcast frequency component is completely removed from the intelligence echo signal being processed at that time is not absolutely critical from an operational standpoint, since, after processing, the intelligence frequencies concomitant therewith actually act as multivibrator operators anyway. Of course, it should be understood that removal of the broadcast signal from the received echo signal during the processing thereof tends to optimize the operation of the subject invention from a signal-to-noise enhancement standpoint. After clipping, the envelope thereof is extracted by diode detector 25 to produce an appropriate signal, the trailing edge of which when applied to multivibrator 26 turns it off provided, of course, as previously mentioned, it occurs prior to the expiration of a twelve millisecond time period.

Accordingly, it may readily be seen that the duration of the negative square wave output of multivibrator 26 is a function of the altitude of the transducer above the sea floor. This signal is then further processed by circuit isolation emitter follower 27 and Zener limiter 28, the latter of which limits the output of the entire transmit-receive circuit to a useful maximum of negative twelve volts.

This negative altitude information output signal is then fed through relay 29 to the input of utilization apparatus controller. Although in this case, said controller included squarewave detector and control amplifiers 32, up-down relays 33, and winch 34, any suitable conventional controller which is responsive to and controls in accordance with the length of a negative square wave output signal may be employed as necessary to fulfill the control requirements of any given operational circumstances or applications. In this particular embodiment, however, a submarine vehicle is intended to be raised or lowered to maintain a substantially constant altitude from the sea floor, as it is being towed by cable 35 from some tractor device, such as a ship or the like.

In order to insure that reflections and/or reverberations from the interface of the air and water at the surface of the sea do not have any deleterious influences on the echo-

ranging process of this invention, pressure switch 136 is installed therein in such manner that 24 volts is properly applied thereto only when the controlled submarine vehicle is at least some predetermined depth below said surface. At that time the transmit-receive portion of the subject invention is energized for echo-ranging and altitude control operations. It should be understood, however, that in the event this feature is not wanted, it would only be necessary to apply -24 direct current volt B— voltage in the appropriate manner to energize the various and sundry stages as shown in FIG. 2B by eliminating or shorting pressure switch 136.

It is, likewise, to be understood that although relay 29 has been incorporated as an intermediate component between the output of the echo-ranging portion of this invention and the input to the utilization apparatus controller, it may be omitted if desired for many practical purposes, inasmuch as the selection thereof is merely a matter of design choice of the artisan and is contingent upon whether or not other associated operations need to be performed. In such instance, the output would obviously be taken from the output of Zener limiter 28. On the other hand, if relay 29 is included, the output therefrom may be taken from any appropriate switch element thereof as required to properly effect performance of said other associated operations.

In this case, the utilization apparatus controller is employed to raise or lower the towed submarine vehicle. This occurs because the squarewave detector and control amplifier functions in accordance with the duration of the negative squarewave to cause up-down relays 33 to, in turn, cause one or more winches 34 to pay out or roll in tow cable 35, and thereby lower or raise the submarine vehicle.

Of course, it would again be obvious to the artisan to make controller 31 regulate any other desired appropriate utilization apparatus.

Obviously, many modifications and other embodiments of the subject invention will readily come to the mind of one skilled in the art having the benefit of the teachings presented in the foregoing description in accompaniment with the associated drawing. Therefore, it is to be understood that the invention is not to be limited thereto and that said modification and embodiments are intended to be included within the scope of the appended claims.

What is claimed is:

1. An echo-ranging system comprising in combination, a transducer, a blocking oscillator coupled to said transducer, a transmit-receive circuit effectively connected to said blocking oscillator and said transducer, tuned amplifier means coupled to the output of said transmit-receive circuit, a shunt detector effectively connected to the output of said tuned amplifier means, a clipper circuit coupled to the output of said shunt detector, a diode detector connected to the output of said clipper circuit, a one-shot multivibrator having a pair of inputs and an output with one of the inputs thereof coupled to the output of the aforesaid blocking oscillator and with the other input thereof coupled to the output of said diode detector, and a Zener limiter effectively connected to the output of the aforesaid one-shot multivibrator.
2. The device of claim 1 wherein said blocking oscillator includes a PNP transistor.
3. The device of claim 1 wherein said transmit-receive circuit comprises, a first diode, a second diode connected in parallel with said first diode in a reversed polarity relationship, and a capacitor connected in series with said parallel connected first and second diodes.

4. The device of claim 1 wherein said tuned amplifier means includes at least one PNP transistor.
5. The device of claim 1 wherein said shunt detector comprises, a resistor, and a capacitor connected in parallel therewith.
6. The device of claim 1 wherein said clipper circuit comprises, a diode, and a resistor connected in parallel with said diode.
7. The device of claim 1 wherein said one-shot multivibrator includes a pair of set and reset PNP transistors.
8. The device of claim 1 wherein said Zener limiter is a Zener diode.
9. An altitude control system comprising in combination, means for timely generating a predetermined frequency signal, means for receiving signals within a predetermined frequency range, means connected to said receiving means for substantially blocking thereto the aforementioned predetermined frequency signal as it is timely being generated by said generating means,
10. An altitude control system comprising in combination, means for timely generating a predetermined frequency signal, means for receiving signals within a predetermined frequency range, means connected to said receiving means for bypassing any of said predetermined frequency signals not blocked by said blocking means, means coupled to said receiving means for shaping the signal therefrom,
11. An altitude control system comprising in combination, means for timely generating a predetermined frequency signal, means for receiving signals within a predetermined frequency range, means connected to said receiving means for producing a signal having a duration that is proportional to the time duration between the generation of said predetermined frequency signal and the reception of a modified version thereof by said receiving means, and a transducer connected to the output of said predetermined frequency signal generating means and the input of said receiving means.
12. The invention according to claim 9 further characterized by means connected to said receiving means for compensating for changes in the ambient temperature thereof.
13. The invention according to claim 9 further characterized by means connected to the output of said proportional duration signal producing means for isolating the circuit thereof and limiting the amplitude of the proportional duration signal therefrom.
14. The invention according to claim 10 further characterized by a controller means connected to the output of said circuit isolation and limiting means.
15. In an altitude control system, means for timely generating a predetermined frequency signal, means for receiving signals within a predetermined frequency range, means connected to said receiving means for substantially blocking thereto the aforementioned predetermined frequency as it is timely being generated by said generating means,
16. In an altitude control system, means for timely generating a predetermined frequency signal, means for receiving signals within a predetermined frequency range, means connected to said receiving means for bypassing any of said predetermined frequency signals not blocked by said blocking means, means coupled to said receiving means for shaping the signal therefrom,
17. In an altitude control system, means for timely generating a predetermined frequency signal, means for receiving signals within a predetermined frequency range, means connected to said receiving means for producing a signal having a duration that is proportional to the time duration between the generation of said predetermined frequency signal and the reception of a modified version thereof by said receiving means, and a transducer connected to the output of said predetermined frequency signal generating means and the input of said receiving means,

a first thermistor connected to said receiving means,
and
a second thermistor connected to the aforesaid propor-
tional duration signal producing means.
